UNITED STATES PATENT OFFICE.

JOSEPH A. BIERNAT, OF BUFFALO, NEW YORK.

PRESSING-BOARD.

1,116,222.

Specification of Letters Patent.

Patented Nov. 3, 1914.

Application filed June 19, 1914. Serial No. 846,115.

To all whom it may concern:

Be it known that I, JOSEPH A. BIERNAT, a citizen of the United States, and residing at Buffalo, in the county of Erie and State 5 of New York, have invented certain new and useful Improvements in Pressing-Boards, of which the following is a specification.

This invention relates to certain new and 10 useful improvements in pressing boards.

The primary object of this invention is in the provision of a cast steel bracket for ironing boards of that class known as press boards and which are especially adapted 15 for use in tailors' use and in pressing cloth and clothing.

A further object is to provide a one-piece bracket adapted to be secured between similar boards preferably arranged in parallelism, such boards being serviceable for ironing 20 articles thereon.

A still further object is to provide a bracket positionable between two pressing boards for firmly mounting the same but at 25 the same time occupying the least possible space between the said boards.

With these general objects in view and others that will appear as the nature of the invention is better understood, the same consists 30 in the novel construction, combination and arrangement of parts to be hereinafter more fully described, illustrated in the accompanying drawings, and pointed out in the appended claim.

In the drawings forming a part of this application and wherein like designating numerals refer to corresponding parts throughout the several views: Figure 1 is a side elevation of the device. Fig. 2 is a 35 top plan view thereof with the top board removed from the bracket. Fig. 3 is an end view of the device. Fig. 4 is a transverse sectional view thereof taken on line IV—IV of Fig. 1, and, Fig. 5 is a similar sectional view on line V—V of Fig. 1.

Referring more in detail to the drawings, the two pressing boards 10 are disclosed as being of identical size and shape and positioned in parallel relation by means of the 40 improved bracket 11. An integral connect-

ing web 15 connects the plates 12 being positioned centrally and longitudinally thereof and having its opposite sides cut-away and faced with curved edge plates 16 forming reinforcing edge flanges thereon and covering the edges of the web and preventing any injury to the articles being pressed by reason of engagement therewith. The arms 55 and adjacent portions of the plates 12 are connected together by a similar web 17 which is substantially X-shaped as best illustrated in Fig. 4, said web 17 being provided with oppositely-arranged V-shaped strengthening ribs 18 which meet and are integral with the central longitudinal web 15. The 60 end arms 13 are each provided on their inner side with arched reinforcing brackets 19 which are substantially T-shaped in cross-section and are adapted to rigidly brace the said arms. The boards 10 are secured to the 65 bracket by means of hold-fast devices such as screws 20 positioned through perforations 21 adjacent the terminals of each of the arms 13 and 14 and also through the perforations 22 at the broader ends of the 70 plates 12. By this construction it will be seen that the bracket member firmly mounts the boards 10 so that the outer surface of either board may be employed to receive the articles to be pressed while the connecting 75 portion of the bracket is contracted so as to afford the least possible obstruction to the articles which are being operated upon, the bracket also being provided with protecting flanges for eliminating some of the sharp- 80 ended edges of the bracket.

While the form of the invention herein shown and described is believed to be the preferable embodiment thereof, it is nevertheless to be understood that various forms, 85 modifications and arrangement of the parts may be had without departing from the spirit and scope of the invention as claimed.

What I claim as new is:—

A bracket for press boards, comprising 90 tapered parallel plates, a longitudinal central web between said plates having substantially curved cut-away forward and rear portions, edging flanges upon said cut-away portions of said web integral with 95

and terminating with said plates, laterally-projecting relatively long and short arms oppositely-positioned in parallelism upon said plates, an X-shaped web between the 5 longer pairs of said arms and being integral with said arms, plates and longitudinal web, oppositely-extending V-shaped reinforcing ribs upon said X-shaped web, and arch-shaped reinforces upon the inner faces of

said relatively shorter arms and integral 1c with the adjacent ones of said plates.

In testimony whereof I affix my signature in presence of two witnesses.

JOSEPH A. BIERNAT.
